UNITED STATES PATENT OFFICE

159,690

TABLE COVER

Elsa A. Squires, Santa Clara, Calif.

Application May 27, 1949, Serial No. 2,920

Term of patent 7 years

(Cl. D33—15)

To all whom it may concern:

Be it known that I, Elsa A. Squires, a citizen of the United States, residing in the city of Santa Clara, county of Santa Clara, State of California, have invented a new, original, and ornamental Design for a Table Cover, of which the following is a specification, reference being had to the accompanying drawing, forming part thereof.

I claim:

The ornamental design for a table cover, as shown.

ELSA A. SQUIRES.
